US0D1086527S

(12) **United States Design Patent** (10) **Patent No.:** **US D1,086,527 S**
(45) **Date of Patent:** **** Jul. 29, 2025**

(54) **FLOODLIGHT**

(71) Applicant: **Amazon Technologies, Inc.**, Seattle, WA (US)

(72) Inventors: **Alexsandra M. Bowers**, Fairview Park, OH (US); **Paul Douglas Grearson**, Salisbury, MA (US); **Ryan David Hruska**, North Royalton, OH (US); **James Siminoff**, Pacific Palisades, CA (US); **Youssef Takhchi**, Cleveland, OH (US); **Treasure Hinds**, Seattle, WA (US); **Greg Janky**, Seattle, WA (US); **Alexandra Specht**, Harvard, MA (US)

(73) Assignee: **Amazon Technologies, Inc.**, Seattle, WA (US)

(**) Term: **15 Years**

(21) Appl. No.: **29/947,917**

(22) Filed: **Jun. 18, 2024**

(57) **CLAIM**

The ornamental design for a floodlight, as shown and described.

DESCRIPTION

FIG. 1 is a top, front, right-side perspective view of a floodlight;

FIG. 2 is a bottom, back, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof;

FIG. 8 is a bottom view thereof; and,

FIG. 9 is a top, front, right-side perspective view of the floodlight shown in use.

The broken lines depict portions of the floodlight that form no part of the claimed design. The broken line subject matter

(Continued)

shown in front of the floodlight in FIG. 9 shows environmental structure and forms no part of the claimed design.
